UNITED STATES PATENT OFFICE.

JOSEPH ACKERLY, OF PASSAIC, NEW JERSEY, ASSIGNOR OF ONE-HALF TO
ANDREW LABASH, OF SAME PLACE.

KEY-GAGE.

SPECIFICATION forming part of Letters Patent No. 683,871, dated October 1, 1901.

Application filed May 6, 1901. Serial No. 58,844. (No model.)

To all whom it may concern:

Be it known that I, JOSEPH ACKERLY, a citizen of the United States, residing at 138 Second street, Passaic, county of Passaic, 5 State of New Jersey, have invented certain new and useful Improvements in Key-Gages, fully described and represented in the following specification and the accompanying drawings, forming a part of the same.

10 The object of the present invention is to furnish a cheap and convenient apparatus for measuring the angle of key-seats in pulleys and wheels where fitted upon a grooved shaft, so that the key to fit such key-seat may be accurately finished without repeated fitting to the seat. Other devices have been made for a similar purpose and with a fixed and adjustable bar such as I employ; but mine is distinguished from others in having 15 one of the gage-bars formed at one end with a lateral slotted arm which, in conjunction with a pivoted link at the other end of the bar and a clamp-screw through the slotted arm, serves to readily adjust the movable bar to 20 the desired angle and to secure it firmly when thus adjusted.

The invention is shown in three different forms in the annexed drawings.

Figures 1 and 2 are an elevation and plan 30 of the key-gage provided with a thumb-screw for adjusting the angle-bar. Fig. 3 is a longitudinal section of a pulley-hub and shaft end with a key-gage in which the angle-bar is adjusted solely by the fingers. Figs. 4 and

35 5 are an elevation and plan of the key-gage having links at opposite ends of the angle-bar and draw-bars attached to both of the links to adjust such bars. The angle-bar is removed and the parts are shown in section 40 in Fig. 5 on line 55 in Fig. 4.

a designates the base-bar, from which a handle *b* may be extended, if desired.

Referring to Fig. 1, *c* is the lateral arm upon the base-bar and is provided with slot *d* and clamp-screw *e*. *f* is the angle-bar, which is perforated for the passage of the clamp-screw and is provided with a link *g* near the opposite end, which link has a pivot *h* fitted through a slot *n* in the end of the 45 base-bar. The link is shown double—that is, with one strap upon each side of the base-

bar and angle-bar. A draw-bar *j* is attached to the pivot *h*, and a clamp-screw *k* is journaled in a bearing *l* upon the base-bar and its thread fitted to a nut *m* upon the draw- 55 bar.

It will be observed that the clamp-screw *e* prevents longitudinal motion of the angle-bar *f*, and the drawing of the pivot *h* toward the bearing *l* by rotating the clamp-screw 60 therefore presses the free end of the angle-bar outward from the base-bar.

When the instrument is inserted in a keyway to measure the angle, as is illustrated in Fig. 3, the arm *c* is retained outside of the 65 keyway, so that the outer end of the angle-bar may be manipulated, and such outer end is pressed out from the base-bar to fit the angle of the keyway when the inner end has been pressed outward by turning the clamp- 70 screw *k*. When both ends of the angle-bar are thus adjusted to the angle of the keyway, the parts are secured together by the thumb-nut *e'* upon the clamp-screw *e*, and the angle of the two bars is thus preserved. 75

In Fig. 3 the construction is simplified by forming a slot *f'* in the angle-bar transverse to the slot in the arm *c*, so that the angle-bar may be pressed longitudinally of the base-bar when both are inserted in the keyway, 80 thus causing the link *g* to carry the angle-bar outward, while the opposite end of the angle-bar is pressed outward with the finger and the clamp-screw then secured to hold the parts in their adjusted positions. 85

A scale of index-marks is shown upon the base-bar in Fig. 3, (the divisions not being numbered for want of room upon the drawings,) and the mark upon such scale which coincides with the outer end of the keyway 90 may be noted when measuring the angle by which the length of the key from the inner end of the base-bar is attained. When the instrument is removed from the keyway, the width of the key at both ends can be readily 95 ascertained by applying a scale or calipers to the instrument at the inner end and at the point where the mark upon the scale coincided with the outer end of the keyway.

With the construction shown in Fig. 3 the 100 adjustment of the angle-bar is effected by pushing it longitudinally and moving its outer

end away from the base-bar, while in the other figures the angle-bar is held from longitudinal movement by the arm *c* and the pivot *h* of the link *g* is movable in the base-bar.

Figs. 4 and 5 show the two bars connected near their opposite ends by two links *g* and *g'*, their pivots *h* and *h'* being fitted to slots *n* and *n'* upon the base-bar and each provided with a draw-bar *i* or *j*, extended to the handle *b*. A clamp-screw *o* is extended through the base-bar, and the draw-bars are provided each with a slot *p*, fitted to such screw.

15 To use the gage thus constructed, the clamp-screws *e* and *o* are loosened, the instrument is placed in the keyway, and the two draw-bars are pulled simultaneously by means of their hooks. The links *g* and *g'* thus force 20 the opposite ends of the angle-bar outward and independently adjusting them automatically to the angle of the keyway. The clamp or screw *o* is then tightened to secure the draw-bars, and the clamp-screw *e* is tightened 25 to secure the angle-bar in its adjusted position.

It will be observed that the clamp-screw *o* serves to lock the draw-bars *i* and *j* when the links and the angle-bar are adjusted and 30 that the thread upon the thumb-screw *k* serves also to lock the draw-bar *j*, which is shown in Fig. 1, when the angle-bar is adjusted, and I have therefore claimed, broadly, the combination, with the draw-bar, of means for locking the same.

Having thus set forth the nature of the invention, what is claimed herein is—

1. In a key-gage, the combination, with the base-bar *a* having the lateral arm *c* at its outer end provided with slot *d* and clamp-screw *e*, of the angle-bar *f* connected with the inner end of the base-bar *a* by link *g*, and clamped to the arm, when adjusted, by the clamp-screw *e*. 40

2. In a key-gage, the combination, with the base-bar *a* having at its inner end the slot *n* and at its outer end the lateral arm *c* provided with the slot *d* and clamp-screw *e*, of the angle-bar *f* jointed upon the clamp-screw and held from longitudinal motion thereby, 50 the link *g* jointed to the angle-bar and having pivot *h* fitted to the slot *n*, a draw-bar for drawing the link toward the outer end of the base-bar, and means for locking such draw-bar when adjusted.

3. In a key-gage, the combination, with the base-bar *a* having at its inner end the slot *n* and at its outer end the slot *n'*, and lateral arm *c* provided with slot *d* and clamp-screw *e*, of the angle-bar *f* jointed upon the clamp-screw as set forth, the links *g* and *g'* jointed to the angle-bar and having their pivots *h*, *h'*, fitted to the slots *n*, *n'*, separate draw-bars attached to the pivots *h*, *h'*, and means for locking the draw-bars when the angle-bar is 65 adjusted.

In testimony whereof I have hereunto set my hand in the presence of two subscribing witnesses.

JOSEPH ACKERLY.
